CASING FOR A WRITING INSTRUMENT

Alfred W. Doux, New York, N. Y., assignor to Alfra Manufacturing Corporation, New York,
N. Y., a corporation of New York

Application May 25, 1948, Serial No. 146,598

Term of patent 7 years

(Cl. D74—17)

To all whom it may concern:

Be it known that I, Alfred W. Doux, a citizen of Brazil, residing at New York, in the county of New York and State of New York, have invented a new, original, and ornamental Design for a Casing for a Writing Instrument, of which the following is a specification, reference being had to the accompanying drawing, forming part thereof.

Fig. 1 is a horizontal plan view of a casing for a writing instrument, showing my new design; and

Fig. 2 is an end view thereof.

I claim:

The ornamental design for a casing for a writing instrument, as shown.

ALFRED W. DOUX.
